Application July 26, 1950, Serial No. 175,924

3 Claims. (Cl. 73—156)

1

This invention relates to card checking machines and especially to the type which are adapted to detect whether the card hole punchings have been made correctly and according to different codes.

The present improvements are especially useful for determining whether card holes already in a card, or to be punched, are out of conformity with an arbitrary code. In one adopted code certain characters are designated by a single hole at differentially disposed index point positions, and any extraneous hole would indicate incorrect punching in a card column. In a preferred alphabetic code the letters A-Z are represented by one hole at any of the digit positions 1-9 (the numerical group) and one hole at the 0, X, R position (the zone group). According to the present invention any double punching or extraneous punching in either the numerical or zone group would be detected when the present double punching detecting means is conditioned to function in this manner. It is desirable at times to permit double hole punching in one of the selected groups, and to enable the detection of any hole which is extraneous to said double hole punching another condition or arrangement of the detecting means may be provided which will approve of the presence of double hole punching in one column but will immediately detect and signal if any additional hole punching is present. Such double hole punching may be either in the zone or numerical group, but is preferably in the zone group and herein holes at both X and R. A hole in any other index point position in this column, such as 1-9 and 0 will be detected.

As one manner of illustrating the present invention the checking arrangement shown herein is employed to detect the correctness of a completely punched card but if so desired it may be employed to determine the correctness of card hole punching as the card is punched, as for example, by the operation of keys. This will prevent improper punching as, for example, punching two holes by an alphabet key when in this particular column a single digit representing hole should have been made.

It is, therefore, the main object of the invention to provide a double hole punching detecting means which will, in the event of numerical punching, detect the presence of any extraneous hole; condition such means so that it will approve of double hole punching in separate zone and numerical groups when alphabetic code punching is to be effected but signal the presence of any extraneous hole in either group, and further condition such means so that it will approve of double hole punching in one of the groups but

2

signal the presence of an improper additional hole or punching in the same or other group.

Other objects of the invention will be pointed out in the following description and claims and illustrated in the accompanying drawings, which disclose, by way of example, the principle of the invention and the best mode, which has been contemplated, of applying that principle.

In the drawings:

10 Fig. 1 is a longitudinal sectional view of the illustrative record sensing machine associated with the present invention.

Fig. 2 is a view in side elevation showing the magnetically operated escapement mechanism for the card carriage.

Fig. 3 is a plan view of the record sensing machine.

Fig. 4 is a fragmentary portion of a conventional record card showing the codes of holes or perforations which are used to represent the letters of the alphabet, the digits and for a special control indication by both X and R for a last column to be punched (column 49 or 80, for example) of the card.

25 Fig. 5 is a diagram of the electrical wiring connections for the instrumentalities of the record sensing machine.

Control record

30 The perforated record which is adapted to be sensed in order to have its perforations checked to determine if the characters they are to represent are made according to a code comprises, as shown in Fig. 4, a well known form of record card C adapted to control electrical accounting 35 printing machines. Differentially positioned control designations, such as perforations 9, are used to represent the various alphabetical and numerical characters representing the data to be entered in and printed by such electrical accounting machines.

40 The perforations are variously positioned in one or more columns of the record card, the letters of the alphabet A-Z being designated by two perforations, one perforation in either of the zone groups 0, X, R and one perforation in the numerical group 1-9. The letters of the first group A-I are designated by a perforation which is always at the R zone index point position in combination with one perforation at the 1-9 index point position. The letters of the second group J-R are designated by one perforation which is always at the X zone index point position in combination with a perforation at the 1-9 index point position. The third group of the letters S-Z is represented by a hole at the 0 zone index point position in combination with a perforation in the 2-9 index point position.

Hence, in the above described system of combinational arrangement of perforations any of the letters of the alphabet A-Z can be designated. It is obvious that each letter of the alphabet is represented by one hole in the zone group and one hole in the numerical group and that the occurrence of more than one hole in either group would provide an extraneous hole which would probably select an alphabet type in the accounting machine which was not intended. By an arrangement to be presently described it is possible to sense whenever more than one hole appears in either group and produce a signal when such has been detected. More specifically, when the machine is conditioned for checking perforations in columns representing alphabetic characters the present checking arrangement detects the presence of more than one hole in the zone group and more than one hole in the numerical group in the same column.

As shown in the card C of Fig. 4 numerical values or digits 0-9 are represented by a single perforation in the corresponding 0 through 9 index point positions and X, R alone may also represent other numerical values. When the present checking arrangement is conditioned for determining whether numerical characters are properly represented the presence of more than one hole in any of the index point positions R through 9 will be indicated as an incorrect punching.

In some instances it is desirable to utilize a selected column for control purposes in the accounting machine by punching holes at two index point positions of one group, such as the R and X index point positions as shown in column 80 of the card shown in Fig. 4. For checking this column the checking arrangement is conditioned to approve of the presence of both of such holes and to also detect the presence of any other hole in the index point position 1-9 and 0 and indicate such error.

Record sensing unit

Referring to Fig. 3 the record cards C to be sensed or analyzed are placed in a magazine designated 10, from which they are advanced singly from the bottom of the magazine by means of a picker 11 toward the left, to present the first column of the card to a card sensing position above the sensing brushes 12 (Fig. 1). In this position the card carriage comprising a pusher 13 (Fig. 1) and a forward transverse guide 14 engages the card and advances it, step by step, under control of the escapement mechanism to be described later. Pusher 13 and transverse guide 14 are carried by an escapement rack 15 and the picker knife 11 is carried by a rack bar 16. Teeth on the underside of rack 15 mesh with a gear 17 (see Fig. 1) and rack teeth on bar 16 mesh with a gear 18, both gears being rigidly mounted on a cross shaft 19 (Fig. 3). Due to this connection between the elements, the movement of picker 11 toward the left, as viewed in Fig. 3, is accompanied by movement to the right of pusher 13 and forward guide 14. At the commencement of operations the picker and pusher are in the position shown in Fig. 3.

The rack 16 is provided with a finger piece 20 at its right-hand extremity by means of which the rack 16 and the picker 11 may be moved toward the left to feed a card from the magazine 10. This movement is accompanied by movement of the pusher 13 in the opposite direction, the parts being so proportioned that, when the

card has been advanced to present its first column to the sensing brushes 12, the pusher 13 will have moved toward the right sufficiently to engage the right-hand, or trailing edge of the card, and will now control the further advancement thereof in response to the operation of the escapement mechanism.

The operation of card feeding just outlined is fully explained in Patent No. 1,772,186, granted to F. L. Lee et al. for a duplicating card punching machine.

The escapement mechanism referred to is of the same general nature as that disclosed in the Schaaff patent, No. 1,426,223 and a brief description thereof will now be given.

When the card is in position above the sensing brushes 12 (Fig. 1), further advance is controlled by the escapement mechanism which, in turn, is responsive to the energization of escape magnet 40. Upon energization of magnet 40 its armature 41 will be rocked about a pivot in a clockwise direction and through a screw 42 secured to an arm 43a projecting from a rockably mounted rod 43, will rock the rod 43 counterclockwise against the tension of a spring 44. The rod 43 is rocked as an incident to each spacing operation and has secured to one end thereof oppositely extending arms 45, 46 (see also Fig. 2). Arm 46 is provided with a laterally extending pin 46a for engagement with an enlarged opening in a stepping dog 47 which is loosely pivoted on rod 43. Opposite arm 45 is provided with a pin 45a extending into a slot formed in the locking dog 48. When rod 43 is rocked arm 46 will, through its pin and slot connection with dog 47, lift the latter out of one of the notches of the rack 15 and at the same time arm 45 will depress locking dog 48 into a notch between the rack teeth. At this time a spring 49 advances the loosely pivoted dog 47 a short distance just sufficient to permit this dog to move above the top of the next tooth. When the locking dog is again raised, stepping dog 47, due to the movement of rack 15, will ride down along the next tooth until it strikes the end thereof and the carriage is thereby arrested. The usual spring drum (not shown) is provided to bias the rack 15 toward the right, as viewed in Fig. 1. The detailed structure in this dog and escapement rack arrangement is well known and need not be further described, and it is sufficient to note that for each energization of the escape magnet 40 the rack 15 is advanced one step or tooth, carrying with it the pusher 13 and forward guide 14, so that the card is likewise advanced one step, each step of advancement being coextensive with the spacing of the columns of the card.

Also in Fig. 2 are shown the well known "floating cam" contacts 149 and 151, one blade of each of which is shifted by an arm 150 which is loosely pivoted on the rod 43 and which has a lateral extension resting upon the upper edge of the stepping dog 47 so that during escapement from one column to another the incidental raising of the stepping dog 47, through arm 150, will open the contacts 149 and 151 during the period that the dog is raised. Contacts 151 are adjusted to close slightly earlier than contacts 149 as the card carriage comes to rest at the next column position, for a purpose to be better understood later.

The card perforation sensing brushes 12 are shown in Fig. 1. Twelve of these brushes are provided and positioned side by side, there being one for each of the usual twelve rows of index point positions of the card. The brushes

12 are mounted in a reciprocable insulating brush holder 90 so that when elevated in a well known manner the brushes 12 make contact with the card and effect electrical connections through the perforations therein with a common contact roller 91.

The machine shown herein is also provided with the well known form of card column readout. The details of construction of such card column readout are not shown or described herein and are shown only in the wiring diagram of Fig. 5 and in a diagrammatic manner. As shown in the wiring diagram a double brush 30 connected to the card carriage has one brush constantly in contact with a current supply strip 31 and as the carriage moves step by step to advance the card the other brush makes successive connection with contact points 32. These contact points are individually wired to plug sockets 33, and from such socket plug connections are made to condition the checking arrangement in various ways, as will be explained.

Wiring diagram

The improvement will be best understood in connection with the wiring diagram of Fig. 5 wherein the current supply is provided by the line sides 34, 35. The means for setting up an individual representation of the hole sensed or analyzed comprises a series of relays designated R9, R8, R7, R6, R5, R4, R3, R2, R1, R0, RX, RR, corresponding to the index point positions or holes which may be made in a column. These relays are selectively energized under control of the associated perforation or hole sensing means or brushes 12, but if so desired they may be punch magnets energized either under control of the sensing means to punch another card, or keys which are operated to effect card hole punching. An illustrative energizing circuit for energizing relay R9 upon sensing a 9 hole is from line side 34, floating cam contacts 149, RE2 relay contacts now closed, a brush making continuous contact with contact roller 91, the "9" brush 12, connecting wire to the R9 relay, escapement magnet 40, to line side 35. Thus, if at the first column position a 9 hole was sensed R9 relay and escapement magnet 40 are energized, and as the card escapes to column 2 floating cam contacts 149 open to deenergize the R9 relay and escapement magnet 40. Of course, the readout brush 30 moves column by column for conditioning the machine for checking hole punching according to the different codes. It will be assumed that the card is punched in the first column, or it could be in any selected column, to represent numerical information, which of course means that for the present numeric code only one relay RR-R9 should be energized. If more than one relay RR-R9 is energized in the numeric single hole code then an error has been made in punching the column. In checking punching according to a numeric code both R98 and R99 relays are deenergized, and their contacts R98-1 and R99-1 are in the position shown in Fig. 5.

1. Checking punching according to numeric code

Each of the relays R9-R1, R0, RX, is adapted to close its "1" contacts; each of which connects these contacts with the line side 34 through escapement contacts 149, RE2 relay contacts, contact roll 91, sensing brush 12, the wire to the energized relay, through its "1" contacts and then to a series circuit to test whether any other relay is concurrently energized. The R9-1 contacts, for

example, when closed due to the presence of a 9 hole, continues a circuit by a wire 36 to the R8-2 transfer contacts, and from the normally closed contacts of R8-2 the circuit extends by a wire 37 to the R8-1 contacts. If there is a supplemental or extra hole in the 8 index point the R8 relay is energized to transfer the R8-1 contacts and the R8-2 contacts, and the circuit from R9-1 contacts and wire 36 is now extended through the R8-2 contacts now transferred, to the error line 38. This series circuit extends serially further than the R8-1 contacts, or any other "1" contacts, and serially through the remaining relay contacts in the same manner and ultimately to the RR2 contacts. Since, as described, R98-1 contacts are closed for numeric code checking R1-1 contacts and R02 contacts are connected through R98-1, thus the error detecting circuit for numeric code is also controlled by the R0 relay. Further, the circuit from R02 and R01 extends through RX2 relay contacts, the RX1 contacts, R99-1 contacts now normal, to RR2 relay contacts, thus also including the RX and RR relays and sensing of X and R holes for determination of extraneous hole punching for checking the numeric code. It is obvious that when any two or more relays R9-R1, R0, RX, RR are concurrently energized the "2" contacts of one relay in conjunction with the "1" contacts of any other relay completes the error circuit wire 38 from line side 34 to the pickup coil of the RE relay to the line side 35. A hold circuit for the RE relay is through its "1" contacts, the normally closed contacts controlled by manual operated error release key K, to line side 34. At the same time a signal light S which is shunted across the H coil is lighted and remains lighted until the key K is depressed.

The RE2 contacts open and thus even if the carriage escapes to the next column the energizing circuit for any of the R9-R1, R0, RX, RR relays and the escapement magnet 40 cannot be completed, and the sensing operation terminates.

Summarizing, one condition of the checking arrangement enables the checking of numeric representing holes to determine whether more than one hole has been made in each column. The energization of any two or more relays when two or more holes are present completes the error circuit and accordingly a signal is given to indicate the error.

2. Checking holes punched according to alphabetic code

Any field of alphabetic data can be selected for checking by making a plug connection 39, shown by way of example, between the plug socket 33 associated with the first card column of alphabetic data to be checked (or the second card column) and a plug socket 50, thereby picking up, by an obvious circuit through escapement contacts 151 a relay 98. The contacts 151 are adjusted to close slightly earlier than contacts 149 to energize R98 (or relay R99 to be mentioned hereinafter) before any of the R1-R9, R0, RX, RR relays. The multiple plug connections 51 re-energize R98 relay for each subsequent column of a field to be checked. Energization of R98 relay opens contacts R98-1, thus splitting the relays into two groups, one the numeric group R9-R1, and one the zone group R0, RX and RR. An energization of one relay R9-R1 in the numeric group and one relay R0, RX and RR in the zone group will be accepted as correct since the subdivision of the circuit and relays requires the

energization of two relays in either of the two groups to complete the error circuit. If the R₁ relay should be the second relay energized in the numeric group its R₁-2 contacts complete the error circuit. The subdivision of the relays to a group of R₀, RX, RR relays enables the circuit to approve of the energization of a single relay but if two of the relays R₀, RX, RR are energized the error circuit is completed. The series error circuit for the zone group is open if R₀ is energized alone and is through the transferred R₀₁ contacts (if R₀ is energized), through the RX₂ contacts now normal, RX₁ contacts now normal, R₉₉₋₁ contacts now normal, wire 52, RR₂ contacts now open. Obviously, if either RX₂ or RR₂ contacts are transferred when RR or RX are energized as a result of an extra hole at R or X, the error circuit will be completed through either of these contacts RX₂ or RR₂. Also RX₁ and RR₂ contacts in combination complete the error circuit through R₉₉₋₁ contacts if both X and R holes are sensed and both RX and RR relays are energized. However, as an alphabetical field is being dealt with, a single hole of the zone group or a single hole of the numeric group will be approved as correct in that obviously only one relay will be energized. Thus, numerical (single hole) punching can be intermixed with alphabetic code punching.

Summarizing, when the circuit is conditioned in this manner one or more columns can be checked for determination of correct alphabetic code punching, and double holes in either the numeric or group zone will be detected and signalled. By provision of a plurality of sockets 50, R₉₈ relay can be picked up at various columns and one or more fields of alphabetic punching can be verified as the carriage moves step by step, and the circuit is accordingly conditioned for this code checking.

3. Checking X, R, joint control indications

As premised hereinbefore, a special column, the last column to be dealt with which may or may not be column 80, is perforated at both X and R and the machine is conditioned for this checking by picking up R₉₉ relay by the plug connection 53. The R₉₉₋₁ contacts are now opened. If R₀ relay is picked up, and in fact any relay of the numerical group R₉-R₁, then the series circuit from line side 34 will be extended through, as explained before, to wire 60 and since RX relay is now energized the RX₂ contacts complete the error circuit. It is unnecessary to have the circuit go beyond RX₂ contacts to detect the extraneous hole because R, X holes always appear together, and checking the superfluous or extra hole against the X hole will suffice. In this instance R and X are energized and both transfer their "2" contacts to connect to the error wire 38 but the opened R₉₉₋₁ contacts prevent completion of the error circuit, and hence a concurrent energization of R and X relays in this code checking is approved and accepted.

While there have been shown and described and pointed out the fundamental novel features of the invention, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. In a machine for determining whether punched holes or the like have been improperly made at index point positions according to two different codes, the combination of means for sensing said card holes, a plurality of relays, one for each index point position, means for energizing said relays according to the sensed holes, an error indicating circuit, contacts operated by each of said relays, means for interconnecting said contacts in such manner that contacts operated by a pair of relays which are energized when two holes are sensed in a column are jointly effective to complete said error indicating circuit to indicate a non-conformity to one code, and means for dividing said relays and associated contacts into two independently functioning groups for preventing the contacts operated by the energization of one relay in one group and one relay in the other group from being effective to complete said error indicating circuit, and for causing the contacts operated by two relays in either of said groups to be jointly effective to complete said error detecting circuit to indicate a non-conformity with another code.
2. An electrical circuit arrangement devised for the purpose of detecting the improper presence of more than one hole in a card column comprising means for simultaneously sensing the card column for determination of the presence of a hole or holes, a plurality of relays, one for each possible hole in a column, means under control of the sensing means for energizing the relays according to hole or holes in the card column, an error indicating circuit, contacts operated by each associated relay, and a circuit network connecting said contacts and error indicating circuit in such manner that upon the energization of one relay and operation of its contacts said contacts are ineffective to complete said error indicating circuit, and that upon the energization of two relays and operation of their contacts said latter contacts are jointly effective to complete said error indicating circuit.
3. In a machine for determining whether holes are properly or improperly punched at index point positions in a card column, the combination of a plurality of relays, one relay for each index point position, means for sensing said holes, means under control of said sensing means for energizing said plurality of relays selectively, according to the hole or holes sensed, an error indicating circuit, contacts operated by each of said relays, and means for dividing said relays and associated contacts into two independently functioning groups and for interconnecting said contacts and said error indicating circuit in such manner that contacts operated by one relay in one group and contacts operated by one relay in the other group are ineffective to complete said error indicating circuit, but a plurality of contacts in either group operated by the energization of more than one relay in either group are effective to complete said error indicating circuit.
